UNITED STATES PATENT OFFICE.

EMANUEL MÜLLER, OF NEW YORK, N. Y.

SELF-SETTING TIME-PIECE.

SPECIFICATION forming part of Letters Patent No. 439,419, dated October 28, 1890.

Application filed December 7, 1889. Serial No. 332,944. (No model.)

To all whom it may concern:

Be it known that I, EMANUEL MÜLLER, a resident of the city of New York, in the county and State of New York, have invented certain 5 new and useful Improvements in Self-Setting Time-Pieces, of which the following is a specification.

This invention relates to a new attachment to clocks and other time-pieces, whereby the 10 same may be made self-setting or self-regulating, the idea underlying the invention being to supply the time-piece with mechanism that will cause it to gain or lose at certain specific intervals in the exact relation in 15 which, without this attachment, the time-piece would lose or gain; or, in other words, it having been ascertained that a certain time-piece loses, say, six minutes during every twenty-four hours, my improved attachment 20 will so regulate the position of the hands as to make the time-piece gain these six minutes during every twenty-four hours, in addition to the ordinary running operation of the time-piece. Moreover, by my improved attachment 25 this adjustment can be set into automatic action during every hour of the twenty-four hours, or during any other desired subdivision of said twenty-four hours.

The invention consists, mainly, in the employment of a certain differential gearing by 30 which the relation of the minute-arbor and its controlling heart-cam can be properly controlled.

The invention also consists in other details 35 of improvement and combinations of parts, that will be hereinafter more fully specified.

In the accompanying drawings, Figure 1 represents a rear elevation of clock mechanism having my improved attachment. Fig. 40 2 is a side elevation, partly in section, of the same. Fig. 3 is a detail view, on an enlarged scale, of the heart-cam and the parts controlling its movement. Fig. 4 is an enlarged longitudinal section of the rear portion of the 45 movement; and Fig. 5 is a detail side view of the catch of the spring which actuates the pawl and that falls into the heart-cam.

The letter A in the drawings represents the minute-arbor of a suitable clock or other 50 time-piece. This minute-arbor is connected with the usual motor for turning it in the proper direction with approximatively proper

speed. At some portion of its length this minute-arbor A carries a snail-cam I, and the minute-arbor also carries a toothed wheel B, 55 which gears into a pinion C on an arbor D of the heart-cam E. The pinion C is loose on the arbor D, but is crowded by friction-springs e, so as to have frictional contact with the arbor and collar thereon, and turn the 60 same whenever this frictional contact is not otherwise overcome, as hereinafter stated.

In the example which I propose to describe for the purpose of illustrating my invention, we will assume that the wheel B has seventy- 65 two teeth and that the pinion C has six teeth. It follows that the arbor D and the heart-cam E will be revolved twelve times during every single revolution of the arbor A, twelve times, therefore, during every hour, and once, 70 therefore, during every five minutes. The snail-cam I, revolving once every hour, controls the action of a spring H, which in turn connects with a pawl G, that actuates the heart-cam E—that is to say, the spring H has 75 a tendency to lift the pawl G against the heart-cam, as in Fig. 1, and is permitted to do so once an hour, when the snail I carries its shoulder past the angle of the spring-carrier H, as in Fig. 1, and when the pawl G 80 does fly against the heart-cam it affects the same in manner analogous to that of all heart cams; but as the snail-cam in moving leaves the position shown in Fig. 1, it gradually crowds the spring H down, and with it 85 the pawl G, which connects with said spring H by means of the pin g, and thus during the entire hour the pawl is away from the heart-cam, as in Fig. 3, flying against it only, as before stated, once during each hour, and 90 then dropping away. The preferable position for the snail is that which will cause the pawl to strike the heart-cam when the minute-hand is opposite the figure 12 on the dial. As regards the spring H, the same is by preference provided with a spring-finger f, which, 95 getting under the gudgeon g, lifts the pawl G, as will appear clearly from an inspection of the lower part of Fig. 3.

The minute-arbor A is capable of sliding 100 in its bearing.

F is a toothed wheel hung on an independent arbor opposite and near to the wheel B, and one of these wheels has small teeth d,

while the other has a flexible facing *b*, but instead of this coupling device *b d* any other suitable coupling device may be employed, the object being to connect the wheels *B* and *F* whenever the arbor *A* is pushed back or inward, or otherwise moved longitudinally, for the same effect might be produced by pulling on the arbor *A*. The wheel *F*, for the purpose of this example, has seventy-five 10 teeth and meshes into a six-leaf pinion *a*, which is rigidly fastened on the arbor *D*.

Now it will be perceived that during the normal action of the clock mechanism the wheel *F* will be carried around by the arbor *D*, which in turn receives its motion through the wheels *B C*, the latter being frictionally mounted upon the arbor *D*. When, however, the clock is to be regulated, the arbor *A* is pushed to couple the wheels *B* and *F* together, 15 and when, now, the arbor *A* is turned the wheel *F* will impart motion to the arbor *D*, because its pinion *a* is rigidly mounted upon said arbor, the pinion *C* being only frictionally mounted; but as the wheel *F* has seventy-five 20 teeth and the wheel *B* seventy-two teeth, it follows that whenever the arbor *A* revolves by the direct coupling of wheels *B F*, the relation of the heart-cam *E* to the minute-hand will by such motion be disturbed 25 one twenty-fourth of the entire movement of the minute-hand during this act of adjustment.

Having thus described the mechanism, I will give one example to render its object 30 more clear. Supposing, after watching a certain clock or other time-piece, it is found that the same runs five minutes too fast during everyday. Then at any one time—say at about twelve o'clock noon—the minute-hand is taken 35 hold of, pushed inward with its arbor, and turned five minutes back on the dial, whereupon the minute-arbor is again released and carried longitudinally forward into its normal position by a suitable spring *m* or other 40 mechanism. While the arbor *A* was pushed inward and turned to represent five minutes on the dial, the heart-cam *E* was turned to represent one twenty-fourth of those five minutes and was brought to that extent out of its 45 normal alignment with the minute-hand. Hence at the end of every hour, when the snail-cam allows the pawl *G* to drop against the heart-cam, this motion will cause the heart-cam to turn the minute-arbor one twenty-fourth of the whole time which the clock is 50 running too fast during a day. Consequently at the end of every hour the clock will regulate itself to make up for lost time, or drop time gained by too-rapid motion. The same character of adjustment will take place if the 55 clock runs too slow instead of running too 60

fast. I have described the invention with reference to a clock which is to regulate itself, as described, once every hour on an adjustment by the minute-hand covering the irregularity of the clock for twenty-four hours; but the same principle can be applied with respect to any other unit of time for regulation and adjustment, and a time-piece could be arranged to regulate itself at longer intervals 65 than one hour or at shorter intervals, as may be desired.

The main feature of invention of course lies in the employment of the differential gears *B F*, whether the same be on the minute-arbor *A* or on any other arbor geared with the same. 75

What I claim, and desire to secure by Letters Patent, is—

1. In a time-piece, the longitudinally-movable arbor *A*, combined by the differential gear-wheels *B F* with a heart-cam *E*, and pinions *C a* therefor, substantially as described, for turning the minute-arbor through said heart-cam, substantially as described. 80

2. The longitudinally-movable arbor *A*, having gear-wheel *B*, combined with the gear-wheel *F* and pinions *C a*, constituting together a differential gear, as described, and with means, substantially as described, for coupling the wheels *B F* and uncoupling the same, and with the heart-cam *E*, pawl *G*, and snail *I*, as specified. 90

3. The longitudinally-movable arbor *A* and its toothed wheel *B*, combined with a loose pinion *C*, having frictional contact on the arbor *D* and with the fixed pinion *a* on said arbor, differential gear-wheel *F*, heart-cam *E*, pawl *G*, and snail *I*, all arranged as specified. 95

4. The minute-arbor *A* of a time-piece, combined by the frictional pinion *C* with the shaft of the adjusting heart-cam *E* for conjoint operation during the normal motion of the clock-work, and with the differential wheel *F* and fixed pinion *a* for setting the heart-cam into 105 the adjusting position, and means, substantially as described, for coupling the arbor *A* to the wheel *F* whenever adjustment is required, as specified. 100

5. In a time-piece, the minute-hand combined with its minute-arbor and with gear-wheels that connect the minute-arbor with the heart-cam *E* and with said heart-cam, the gear-wheels being arranged as described, so that by moving the hand a certain distance 115 the heart-cam will be turned a given fraction of said distance, as specified.
